UNITED STATES PATENT OFFICE.

ROBERT C. DAVIDSON, OF EVANSTON, WYOMING TERRITORY.

IMPROVEMENT IN FLOOR-CLAMPS.

Specification forming part of Letters Patent No. 146,170, dated January 6, 1874; application filed October 11, 1873.

To all whom it may concern:

Be it known that I, ROBERT C. DAVIDSON, of Evanston, in the county of Uintah and Territory of Wyoming, have invented a new and Improved Floor-Clamp, of which the following is a specification:

The invention will first be fully described, and then pointed out in the claims.

Figure 1 is a side elevation of my improved clamp. Fig. 2 is a section on the line *xx*, and Fig. 3 is a detail of the adjustable connection.

Similar letters of reference indicate corresponding parts.

A and B represent the bars; C, the pointed stud, pins, or screws in the lower ends; D, the connecting-screw a short distance above the stud-screws; E, the lever for clamping the bars on the joist F; H and I, the catch for holding the fastening-lever; G, the plate for protecting the edge of the flooring, and I' the pawl for holding the clamp after clamping up the flooring. The connecting-screw D has a nut, J, for adjusting the bar B to and from the other, according to the thickness of the joist to which the clamp is to be fastened. A key, L, is fixed in said screw to cause the nut and bar B to shift together. Said key shifts along the screw with the nut and bar in a groove in the screw. Another set of pointed stud-

screws, M, is provided in the bars, near the connecting-screw D, for screwing into the joist to hold the clamp when it may be necessary to release the lower screws to shift them forward to get a new hold, in case the flooring is not clamped up sufficiently by the first operation. The bar A is provided with clips N for the application of a lever, O, in case powerful leverage is required. P represents the flooring to be clamped.

The bars A B are placed in the joist F close to the edge, and fastened by the screws C. The upper end of the clamp is then pressed forward, so as to press the flooring together by the plate G, as will be readily understood.

Having thus described my invention, I claim as new and desire to secure by Letters Patent—

1. The key L, nut J, and grooved screw D, combined with bars A B, as and for the purpose described.
2. The combination, with the bar A having clips N N and the inwardly-racked bar B, of the slotted and pivoted bar E having detent H I, as and for the purpose specified.

ROBERT C. DAVIDSON.
